UNITED STATES PATENT OFFICE.

ERNEST S. BOWKER, OF CHICAGO, ILLINOIS.

CORSET-FASTENING.

SPECIFICATION forming part of Letters Patent No. 723,234, dated March 24, 1903.

Application filed March 10, 1902. Serial No. 97,542. (No model.)

To all whom it may concern:

Be it known that I, ERNEST S. BOWKER, a citizen of the United States, residing at Chicago, county of Cook, State of Illinois, have 5 invented a certain new and useful Improvement in Corset-Fastenings; and I declare the following to be a full, clear, and exact description of the invention, such as will enable others skilled in the art to which it pertains 10 to make and use the same, reference being had to the accompanying drawings, which form a part of this specification.

My invention relates generally to fastening devices, and more particularly to devices for 15 positively fastening together the steels in the front of corsets.

Considerable annoyance is often experienced in the use of corsets provided with the usual form of clasps for connecting the steels, 20 owing to the accidental unfastening of the clasps, due to the movement of the body of the user when stooping or bending—as, for instance, in picking up an article from the floor.

25 The object of my invention is to provide a clasp to be secured to one of the steels of a corset, which may be readily engaged with and disengaged from the usual stud on the other corset-steel, but which will not be accidentally unfastened by the movement of the body of the wearer of the corset.

A further object of my invention is to provide a corset-fastener which will be simple in construction, inexpensive in manufacture, 30 and efficient in use.

My invention, briefly described, consists in a clasp adapted to be secured to one of the steels of a corset and provided with an aperture to receive a stud on the other corset-steel of less width than the diameter of the head of the stud, part of the aperture being 40 formed in a resilient tongue extending across the steel to which it is secured and having an offset in the portion thereof above the edge 45 of the steel, whereby the entire flexibility of the tongue is utilized both in the insertion and removal of the head of the stud.

My invention will be more fully described hereinafter with reference to the accompanying drawings, in which the same is illustrated in a convenient and practical form, and in which—

Figure 1 is an elevational view showing the front steels of a corset provided with my improved clasp; Fig. 2, an enlarged plan view 55 of the clasp detached from the corset-steel; and Figs. 3, 4, and 5 sectional views taken on line 33, Fig. 1, showing the stud being inserted in, removed from, and in normal position in the clasp, respectively. 6c

The same reference characters are used to indicate the same parts in the several figures of the drawings.

Reference-letters A and B indicate the steels which are provided at the front of corsets and to which the fastening devices are ordinarily secured. The steel B is provided with a series of studs b, secured thereto in any suitable manner and located at predetermined intervals apart. The studs b are 70 such as are usually employed to engage clasps secured to the other corset-steel.

a indicate fastening devices of common construction secured to the corset-steel A in any suitable manner, as by means of rivets, 75 and provided with apertures to receive the heads of the studs b. The apertures in the clasps a are usually of keyhole shape, the larger portion of the aperture being slightly larger in diameter than the heads of the 80 studs, while the restricted slots communicating with the enlarged portions of the apertures are of a width slightly greater than the necks of the studs, but of less diameter than the heads of the studs. When the corset- 85 steels are moved toward each other, the heads of the studs at once pass through the enlarged portions of the apertures in the clasps and permit the steels to separate at the point of unfastening. It is consequently desirable 90 to provide one or more clasps which will prevent the accidental passage of the head of the stud through the aperture in the clasp.

c indicates a clasp embodying my improvement, which consists in a resilient tongue 95 C', preferably formed integral with the clasp and projecting within the opening in the clasp, which results from the formation of the resilient tongue. The detached end of the resilient tongue is provided with a slot 100 c', extending to the edge of the tongue and of a width less than the diameter of the head of the co-operating stud. A slot c is formed in the clasp of a width corresponding to the

slot c' . The slot c is so located as to aline with the slot c' , as clearly indicated in Fig. 2.

The tongue C' is preferably provided with an offset c^2 intermediate of its length. The 5 offset permits the tongue C' , which normally is located as shown in Fig. 5, to readily bend to the position shown in Fig. 4 when the stud is being disengaged from the clasp. The 10 flexibility of the entire length of the tongue C' is thereby utilized in disengaging the stud from the clasp as well as in inserting the same in the clasp.

The clasp C may be secured to the corset-steel in any suitable manner—as, for instance, 15 by rivets—and one or more of such clasps may be secured to the corset-steel in addition to one or more clasps a of ordinary construction. In Fig. 1 I have shown two clasps C , secured to the top and bottom of the steel A ; 20 but it is obvious that the number and position of such clasps may be varied, as experience may prove desirable.

The operation of my improved corset-fas- 25 tener is as follows: The stud at the point op- posite the clasp is pressed against the resili- 30 ent tongue C' , thereby lifting the same, as in- dicated in Fig. 3, to such a position that the neck of the stud may slide into the slot c , thereby permitting the head of the stud to 35 pass laterally out of the path of movement of the tongue, which then returns to its normal position. The stud may be disengaged from the clasp by relatively moving the cor- 40 set-steels toward each other, so that the neck of the stud engages the slot c' in the resilient tongue. The latter may then be depressed, as shown in Fig. 4, so that the head of the stud is slightly below the plane of the clasp C , and may be therefore disengaged therefrom.

45 It will be observed that in order to disen- gage a stud from my improved clasp it is necessary that the corset-steels should first be moved toward each other, then relatively in planes transverse thereto, and then away 50 from each other, and consequently there is little liability of the accidental disengagement of the stud from the clasp. The resili- 55 ency of the tongue C' , which may be determined by its length, is such as to permit the ready engagement and disengagement of the stud from the clasp, but is sufficient to prevent the necessary movement of the tongue to disengage the stud from the clasp by the force which would ordinarily be exerted by the movement of the body of the wearer.

While I have described more or less pre- cisely the details of construction, I do not wish to be understood as limiting myself thereto,

as I contemplate changes in form, the pro- 60 portion of parts, and the substitution of equivalents, as circumstances may suggest or render expedient, without departing from the spirit of my invention.

Having now fully described my invention, what I claim as new, and desire to secure by 65 Letters Patent, is—

1. In a corset-fastening, the combination with a metal clasp, of a resilient tongue having an offset between its end and its point of connection with the clasp and comprising a 70 portion between the offset and its end located in the same plane as the clasp and a portion between the offset and point of connection with the clasp lying in a plane above that of the plane of the clasp, but adapted to 75 bend into contact with the steel to permit the entire resiliency of the tongue to be utilized in the removal as well as the insertion of the stud, said clasp and tongue having alined slots therein. 80

2. The combination with a corset-steel, of a clasp secured to and extending across the corset-steel and projecting beyond an edge thereof, a resilient tongue located in the open center of and secured to said clasp and ex- 85 tends above but normally out of contact with the corset-steel substantially the entire width of the corset-steel, but adapted to bend into contact with the steel to permit the entire resiliency of the tongue to be utilized in 90 the removal as well as the insertion of the stud, said tongue and clasp having alined slots therein.

3. The combination with a pair of corset- 95 steels, of a stud secured to one steel, a clasp secured to and projecting beyond the edge of the other steel, a resilient tongue located in the open center of and secured to said clasp and comprising an end portion in the same plane as the clasp, an offset located above the 100 edge of the steel and a portion between the offset and the point of connection with the clasp normally lying above the corset-steel, but adapted to bend into contact with the steel to permit the entire resiliency of the 105 tongue to be utilized in the removal as well as the insertion of the stud, said tongue having a slot extending to its outer end in alinement with a slot formed in the clasp.

In testimony whereof I sign this specifica- 110 tion in the presence of two witnesses.

ERNEST S. BOWKER.
